UNITED STATES PATENT OFFICE.

CHARLES S. MOTT, OF PATCHOGUE, ASSIGNOR TO HIMSELF, AND GEORGE H. SHAFFER, OF BROOKLYN, NEW YORK.

MAST-HOOP.

SPECIFICATION forming part of Letters Patent No. 391,548, dated October 23, 1888.

Application filed July 31, 1888. Serial No. 281,541. (No model.)

To all whom it may concern:

Be it known that I, CHARLES S. MOTT, of Patchogue, in the county of Suffolk and State of New York, have invented a new and useful Improvement in Mast-Hoops, of which the following is a full, clear, and exact description.

This invention relates to mast-hoops of the class which are formed of two separate sections hinged to each other and provided with a spring-catch for locking the sections together, so that they can be applied directly to or removed from the mast of a vessel without the need of sliding them on or off the end of the mast.

15 The object of the invention is to simplify, strengthen, and otherwise improve the construction both of the hinge-joint and of the locking and unlocking joint; and to this end the invention consists of a novel construction and 20 arrangement of parts, substantially as herein-after fully described, and distinctly claimed.

Reference is to be had to the accompanying drawings, forming a part of this specification, in which similar letters of reference indicate 25 corresponding parts in all the figures.

Figure 1 is a plan view, partly in section, of a mast-hoop embodying my invention. Fig. 2 is an edge view of the same. Fig. 3 is a cross-section of the locking-joint of the same 30 on the line $x-x$, Fig. 1. Fig. 4 is a cross-sectional view of the hinge-joint of the same on the line $y-y$, Fig. 1.

The mast-hoop thus illustrated is formed of two opposite semicircular wooden sections, A A', the cross-section of each of which shows the usual convex inner edge and flat outer edge.

35 The hinge B, by which the ends of the sections A A' are permanently jointed together, is formed of two metallic sleeves, C C', curved 40 lengthwise on the circle of the complete hoop and having the flattened elliptical cross-section thereof, so as to fit tightly over the respective meeting ends of the hoop, as shown, and with the straight-end edges of the sleeves 45 C C' are formed integrally hinge-eyes D D', through which a hinge-pin, E, is passed to complete the joint. The sleeves C C' are preferably riveted to the respective sections A A', as indicated.

50 To each sleeve C C' is permanently united a

metallic strap, F, which is carried around and riveted to the flat periphery of the corresponding wooden section, and the farther ends of the straps F are also permanently attached to metallic sleeves G G', of like shape with the sleeves C C', fitted tightly over the releasable ends of the respective sections A A'. The releasable end of the section A, together with the sleeve G thereon, is made of such a size as to slide freely but closely in the sleeve G', which projects considerably beyond the end of its section A', and in the cylindrical outer side of the metallic sleeve G and wooden section A is formed a longitudinal slot, H, the bottom H' of which is approximately straight, 65 and which is thus deeper at its middle than at its ends.

In the slot H is arranged a flat metallic spring-strip, I, the ends of which are attached to the bottom H' of the slot, but the middle 70 part of which is free to yield inward and to spring outward when released, and carries a beveled catch, J, which automatically engages a slot, K, in the outer cylindrical wall of the meeting sleeve G', when the sections A A' are 75 pressed together, but which can be easily pressed inward by the thumb-nail to release the two sections and allow them to be spread apart.

Having thus described my invention, what I 80 claim as new, and desire to secure by Letters Patent, is—

1. The combination, with the jointing ends of two wooden semicircular hoop-sections having a cross-section flattened on the outer side, 85 of two metallic sleeves curved lengthwise on the circle of the hoop, having the same flattened cross-section therewith, and having eye-lugs formed integrally with their respective flattened meeting edges, the said sleeves being 90 fitted on the ends of the wooden sections, and a hinge-pin passed through the eye-lugs on the two sleeves, substantially as described.

2. The combination, with the meeting ends of two wooden semicircular hoop-sections, of a 95 metallic sleeve curved lengthwise on the circle of the hoop, fitted on but projecting beyond the end of one section and having a slot in its outer longitudinally-curved side, a metallic sleeve of like shape with, but smaller than and 100

adapted to slide in, the first sleeve, fitted wholly on the end of the other wooden section, a longitudinal slot having an approximately straight bottom formed in the outer curved 5 side of the latter sleeve and of the corresponding wooden section, and a spring-strip seated in the said slot and having a yielding beveled catch on its middle part to engage the slot in the outer sleeve, substantially as described.
